LIQUID APPLYING MACHINE

William C. Card, Winthrop, Mass., assignor to
Compo Shoe Machinery Corporation, Boston,
Mass., a corporation of Delaware

Application August 28, 1943, Serial No. 500,382

5 Claims. (Cl. 12—80)

This invention relates to machines for applying a stripe of liquid to irregularly shaped articles and more particularly to machines for applying a marginal stripe of adhesive or adhesive softener to the soles of shoes in a manufacturing operation preliminary to the cementing of the soles to shoe uppers.

In the manufacture of cemented shoes, it is common practice to apply adhesive to the overlusted margin of the shoe upper and to the marginal edge of the attaching face of the outsole, allow the adhesive to dry and then apply an adhesive softener to the outsole and/or upper just prior to placing the parts in a press for the cementing of the sole to the upper.

This invention provides an improved machine for applying automatically, marginal stripes of adhesive or adhesive softener to the soles. In the illustrated embodiment of the invention, a pair of rotary brushes dip into the adhesive or softener to be applied and are guided by the edge of a sole advanced through the machine. Pressure rolls maintain the sole at the proper pressure against the brushes and against the mechanism for feeding the sole through the machine. A foot treadle when depressed by the operator of the machine moves the brushes apart and lifts the pressure rolls so that a sole may be placed in the machine, and when the treadle is released by the operator, the brushes, pressure rolls and guide rolls are moved into operating positions and the sole is fed automatically through the machine with the application of the adhesive or adhesive softener by the brushes.

An object of the invention is to apply a marginal stripe of adhesive or adhesive softener to irregularly shaped articles, such as shoe soles, automatically, by an improved machine.

Another object of the invention is to provide a liquid applying machine having suitable devices for allowing liquid to be applied to opposite marginal edges of a shoe sole, simultaneously, and for allowing the liquid applying to be started or discontinued by the operator, at any desired point along the sole.

Other objects of the invention will in part be obvious and will in part appear hereinafter.

The machine accordingly comprises the features of construction, combination of elements, and arrangement of parts, which will be exemplified in the construction hereinafter set forth and the scope of the invention will be indicated in the claims.

For a fuller understanding of the nature and objects of the invention reference should be had

to the following detailed description taken in connection with the accompanying drawings in which:

Fig. 1 is a plan view looking downwardly upon a machine embodying this invention;

Fig. 2 is a sectional view taken substantially along lines 2—2 of Fig. 1;

Fig. 3 is a sectional elevation taken substantially along lines 3—3 of Fig. 2;

Fig. 4 is a partial plan view looking downwardly on one end of the machine and illustrates the adhesive applying brushes separated and the pressure rolls moved away from their working positions;

Fig. 5 is a sectional view taken substantially along lines 5—5 of Fig. 4;

Fig. 6 is a sectional view on an enlarged scale showing the brackets for moving the feed pressure roll which presses the sole into contact with the feed wheel;

Fig. 7 is a sectional elevation similar to Fig. 3 but illustrates the applying brushes spaced apart and the pressure rolls elevated for the insertion of or removal of a sole from the machine, and

Fig. 8 is a partial plan view looking downwardly upon the machine and illustrates a shoe sole to which liquid is being applied, about halfway through the machine.

Referring to the drawings, there is shown a liquid applying machine having a frame portion 10, in opposite walls of which, is journaled a shaft 11. The gear 12 is secured to one end of the shaft 11 and meshes with a gear 13 secured to a shaft 14 also journaled in the frame 10. A pulley 15 secured to the end of the shaft 14 is belted to a suitable motor or drive shaft (not shown) which serves to rotate the shafts 11 and 14 in opposite directions.

The two circular brushes 16 are clamped to the holders 17 which are slidably keyed to the shaft 11 so that the brushes and their holders can slide towards and away from each other and at the same time rotate with the shaft.

The brushes 16 dip into the liquid bowl 18 which is secured to the frame 10 by the screws 19 so that it may readily be removed for cleaning. Liquid is supplied from the container 20 through the piping 21 and constant level device 22, the valve 23 being provided for cutting off the supply when the bowl 18 is removed.

The brackets 25 are provided with extended fork portions 26 which straddle the hubs of the brush holders 17. The brackets 25 are mounted on the guide studs 27 which extend through

the bearings 28 cast on each side of the machine frame 10.

The levers 30 which have rotatably attached to their inner ends, the rubber covered idler rolls 31, are pivoted to the brackets 25 at 32. The rolls 31 serve to press the sole S against the brushes 16 as illustrated by Figs. 2 and 3. The pressure of the rolls 31 is regulated by the springs 33 which extend between the shoulders 34 on the brackets 25, through bores in the levers 30 and against the washers 35, the positions of which and accordingly the tension of the springs 33, are adjustable by the screws 36 and their associated lock nuts 37.

The arms 40 are pivoted at their outer ends to the frame of the machine at 41 and have threaded in their inner ends, the studs 42 upon which are rotatably mounted the sole edge engaging rolls 43. The studs 42 extend through the arms 40 and are provided with rolls 44 which engage in slots 45 in the brackets 25. Movement of the arms 40 towards and away from each other causes, through the engagement of the studs 42 in the slots 45 in the brackets 25, the brackets to move towards and away from each other respectively, the guide studs 27 on which the brackets are mounted, sliding through the bearings 28 to permit this movement. The brushes 16 are moved with this movement of the brackets 25 through the contact of the lower straddling portion 26 of the brackets contacting the hubs of the holders.

The sole edge guide rolls 43 on the studs 42 contact the edges of the sole S as it is fed through the machine, and through moving the arms 40, the brackets 25 and the brushes 16, cause the brushes to contact the marginal areas of both edges of the sole. The tension springs 46 and 47 which are attached to the arms 40 and to the frame of the machine, urge the arms 40 towards each other and thus hold the guide rolls 43 against the edge of the sole.

The toothed feed wheel 48 is attached to the shaft 14 on which is mounted the gear 13 described in the foregoing, and which continuously rotates the shaft 14 and the feed wheel 48 while the machine is in operation. The rubber covered pressure roll 49 above the feed wheel 48, is mounted for free rotation upon the shaft 50 which is anchored to the arms 51 by the set screws 52 as shown most clearly by Fig. 6. The arms 51 are pivoted to the lugs 53 on the cover of the machine together with the bracket 54 about the pivot pins 55. The set screws 56 screwed into the brackets 54, press the springs 57 against the arms 51 and provides for adjustment of the pressure of the roll 49 against the sole.

The brackets 54 are slotted at 58 to engage the pins 59 which are attached to the extended arms 60 of the yokes 61. When the yokes 61 are moved downwardly as will be described, the pins 59 in the slots 58 of the bracket 54, move the bracket about the pivot pins 55 causing the brackets to lift the pressure roll 49.

The yokes 61 have threaded therein the screws 62 which support the clevis 63. The rolls 64 (Figs. 3 and 7) are rotatably mounted to the lower end of the clevis 63 and contact the outer ends of the levers 30 and serve to depress the outer ends of the levers 30 for lifting the pressure rolls 31 as will be described.

The yokes 61 are attached to the studs 65 which extend through the frame of the machine and which are attached to the tie-rod 66 (Fig. 2).

In the center of this tie rod there is a block 67 carrying a hook 68 to which the hook 69 of a foot treadle (not shown) is attached. The block 67 engages the forked end of the lever 70 which is secured to the shaft 71 journaled in the frame of the machine. The other end of the lever 70 has a cam surface 72 which extends between the rollers 73 which are rotatably mounted at one end of the slide 74. The blocks 75 and 76 which are bolted to the frame of the machine, extend through the grooves 77 and 78 respectively in the slide and serve to guide the slide as it is moved forward (to the right facing Fig. 8 of the drawings) by turning movement of the lever 70 when the foot treadle is depressed.

The springs 80 extend around the upper portions of the studs 65 between the yokes 61 and the frame of the machine and act when the foot treadle is not depressed, to press the yokes 61 and the studs 65 upwardly whereby the rolls 31 and 49 are maintained in work contacting positions.

The slide 74 has the angled walls 81 which when the slide is moved forwardly by the depression of the treadle and the turning movement of the lever 70 about its pivot 71, strike against the angled extension walls 82 on the arms 40 and spreads the arms 40 apart against the resistance of the springs 46 and 47 and spreads the brushes 16 apart as illustrated by Figs. 4 and 7, through the movement of the studs 42 in the slots 45 in the brackets 25 as has been described. When the treadle is released the weight of the long arm of the lever 70 causes a reverse turning movement of the lever 70 and the cam surface 72 being in engagement with the rolls 73 returns the slide 74 to the position shown in Fig. 2 and the springs 46 and 47 urge the brushes 16 into work contacting position.

In operation, the operator of the machine through depressing a treadle which is not shown, causes the treadle to pull down the hook 68, the block 67, the tie rod 66 and the studs 65, overcoming the resistance of the springs 80. The studs 65 pull the yokes 61 downwardly and this causes the rolls 64 to push the outer ends of the levers 30 downwardly causing the inner ends on which the rolls 31 are mounted to move upwardly to lift the rolls 31 to the position shown by Fig. 7.

At the same time, the pins 59 attached to the yokes 61 move the brackets 54 about the pivot pins 55 causing the brackets to lift the pressure roll 49 to the position shown by Fig. 7.

At the same time, the short arm of the lever 55 70 is moved downwardly about its pivot 71 causing the cam surface 72 on its long arm to move the slide 74 inwardly so that its angled walls 81 press against the angled walls 82 on the arms 40 thereby moving the arms 40 apart and spreading the brushes apart as illustrated by Figs. 4 and 7.

The operator then places the sole S to be worked upon, in the machine with the toe at about the center line of the brushes 16 and the forepart over the feed wheel 48. The treadle is then released whereupon the springs 80 cause the studs 65 to move upwardly; the slide 74 is moved rearwardly permitting the brushes 16 to be moved by the springs 46 and 47, together until the guide

rolls 43 strike the edge of the sole; the upward movement of the yoke 61 removes the rolls 64 from contact with the levers 30 permitting the pressure rolls 31 to move downwardly to press the sole against the brushes 16 and finally the upward movement of the yoke 61 moves the

brackets 54 to cause the pressure roll 49 to press the sole against the feed wheel 48.

The feed wheel 48 and the brushes 16 are rotated continuously so that the feed wheel feeds the sole through the machine while the brushes 16 apply liquid from the bowl 18 to the margin of the sole.

After the sole has been fed through the machine to the desired extent, the operator again depresses the foot treadle whereupon the pressure rolls are moved away from the sole, and the brushes are spread apart, and the sole then removed from the machine.

Since certain changes may be made in the above construction and different embodiments of the invention could be made without departing from the scope thereof, it is intended that all matter contained in the above description or shown in the accompanying drawings, shall be interpreted as illustrative and not in a limiting sense.

Having thus described my invention, what I claim as new and desire to secure by Letters Patent of the United States is:

1. A machine for applying liquid to the surface of an article, comprising means for feeding the article through the machine, means including means guided by the edge of the article for applying liquid to the margin of the surface thereof, rollers for pressing the article towards said liquid applying means and arranged to partake of the guided movement thereof, and means including coordinated means actuated by the operator of the machine for moving said liquid applying means and said pressing means away from said surface whereby the article may be removed from the machine.

2. A machine for applying liquid to the surface of an article, comprising means for feeding the article through the machine, means including means guided by the edge of the article for applying liquid to the margin of the surface thereof, means for pressing the article towards said feeding means and arranged to partake of the guided movement thereof, and means including coordinated means actuated by the operator of the machine for moving said liquid applying means and said pressing means away from said surface whereby the article may be removed from the machine.

3. A machine for applying liquid to the sur-

face of an article, comprising means for feeding the article through the machine, means including means guided by the edge of the article for applying liquid to the margin of the surface thereof, means for pressing the article towards said liquid applying means and arranged to partake of the guided movement thereof, means for urging the article into engagement with said feeding means, and means including coordinated means actuated by the operator of the machine for moving said liquid applying means and said pressing means away from said surface and for restraining said urging means whereby the article may be removed from the machine.

4. A machine for applying liquid to the surface of an article comprising a feed wheel for feeding the surface through the machine, a pair of rotary brushes for applying liquid to the opposite marginal edges of the surface, means for supplying liquid to said brushes, means including means for contact with the opposite edges of said outsole for guiding said brushes along said surface, means for rotating said brushes and said feed wheel, means including a pressure roll for pressing said article against said brushes, means including a pressure roll for pressing said article against said feed wheel, and means including coordinated means actuated by the operator of the machine, for separating said brushes and for removing said rolls from contact with said article whereby said article may be removed from the machine.

5. A machine for applying liquid to the surface of an article comprising a feed wheel for moving said article through the machine, a pressure roll opposite said wheel for pressing said article against said wheel, a pair of rotary brushes for applying liquid to said surface, means for supplying liquid to said brushes, means including means for contact with the opposite edges of said article for guiding said brushes along said surface, a pair of pressure rolls, one opposite each of said brushes for pressing said article against said brushes, means for rotating said feed wheel and said brushes, and means including coordinated means actuated by the operator of the machine for moving said guiding means and said brushes apart and for moving said rolls away from said article whereby said article may be removed from the machine.

WILLIAM C. CARD.
